DESIGN FOR A HANDLE FOR KITCHEN UTENSILS OR SIMILAR ARTICLES

Myron J. Zimmer, Chicago, Ill., assignor to Edward Katzinger Company, Chicago, Ill., a corporation of Illinois

Application April 13, 1936, Serial No. 62,086

Term of patent 14 years

To all whom it may concern:

Be it known that I, Myron J. Zimmer, a citizen of the United States, residing at Chicago, in the county of Cook and State of Illinois, have invented a new, original, and ornamental Design for a Handle for Kitchen Utensils or Similar Articles, of which the following is a specification, reference being had to the accompanying drawing, forming part thereof.

Fig. 1 is a side elevational view of a handle for kitchen utensils or similar articles embodying the present design.

Fig. 2 is a transverse section taken along line 2—2 of Fig. 1.

The shading shown on the body of the handle in Fig. 1 is intended to represent contrasting color effect.

I claim:

The ornamental design for a handle for kitchen utensils or similar articles, as shown and described.

MYRON J. ZIMMER.
